UNITED STATES PATENT OFFICE.

GEORGE W. DINGEE, OF UTICA, NEW YORK.

APPARATUS FOR FORMING AND HANDLING PAPER ROLLS.

Application filed June 8, 1922. Serial No. 566,831.

This invention relates to rolls of paper, method of forming, and devices for forming and handling the same.

In the ordinary method of manufacturing paper, such as newsprint-paper, the finished paper taken from the dryer and calendar rolls of the paper making machine is rolled onto large rolls known as stock rolls. The paper making machine is usually provided with devices so that the finished product can be rolled upon at least two such rolls. The finished paper forming stock rolls is then passed about suitable rolls to a slitter and trimmer and to a winding mechanism where it is wound in rolls of the proper size to suit the customer. The winding mechanism usually comprises a pair of power driven drums about which the slitted and trimmed paper is passed and on top of these drums the finished roll of paper is formed. In forming this roll of paper the end of the web is wrapped about a pipe, and the pipe and paper rested upon the top of the drums. The frictional contact between the drums and paper causes the pipe to roll about and wind the paper thereon. In mills making newsprint-paper it is common to form two 72 inch rolls of paper simultaneously on two pieces of 4 inch pipe. The finished rolls are then ready for shipment to the printing establishment, the iron pipes being retained in the roll. In the pressroom a long shaft is passed through the pipe, this shaft being provided with devices for cooperating with an adjustable brake carried on the printing-press so that a drag may be imposed on the roll of paper as it is being drawn into the press. As it is inconvenient to fasten the shaft and pipe together, it is usual to drive a clutch into the end of the paper roll. This mutilates the inner quarter inch of the paper roll, so that it is not suitable to be carried through the machine and made into finished newspapers. This amount of paper is scrap and must be disposed of as such.

After the used paper and the scrap have been removed from the iron pipes, these pipes are stored until a sufficient number accumulate to fill a freight car whereupon they are returned to the paper mill.

The procedure thus outlined is standard in most paper making and newspaper plants.

It has great disadvantages. There is an enormous investment in iron pipe and in facilities for warehousing. Its depreciation is very rapid and considerable labor is entailed in accounting for and handling the pipe, both at the paper mill and in the printing plant. These disadvantages are insignificant as compared with the freight charges for shipping the pipe back and forth. It is shipped as "paper", at a high freight rate, to the printing establishment and then must be returned as iron pipe to the paper mill. Owing to the distances separating paper mills and printing establishments consuming large amounts of paper, the enormity of this expense is obvious.

The invention relates to an improved method of putting up rolls of fabric such as paper for printing presses and similar materials and consists in winding a roll thereof on to a core so constructed that it can be contracted or expanded at will to remove it from the roll when completed or to mount the roll on a similar core for unwinding, and providing means for preventing the center of the roll from unwinding or otherwise collapsing after the core has been removed.

An object of the present invention is to provide an improved method of rolling the paper whereby it is possible to eliminate the trouble and expense incident upon handling the iron pipes. A further object of the invention is to provide devices for use in carrying out this method.

More specifically an object of the present invention is to make a core out of the first few turns of paper as it is being rolled.

A further object of the invention is to provide a pasting device by which adhesive is applied to the paper to form the inner part of the roll so that the paper may itself become a pasted core.

A further object of the invention is to provide devices whereby the amount of paper to be used in making this core is automatically determined.

The invention also contemplates the mounting of a light tube on the core and winding the fabric thereon so that when the core is contracted and removed the tube will prevent unwinding and retain the hole through the roll substantially cylindrical.

It further consists in forming a tube on the core of the fabric being wound, by coating at least one surface of the fabric with an adhesive material for a predetermined number of revolutions of the core and then winding the balance of the roll in the ordinary manner without adhesive material.

Other objects of the invention will be obvious as the description proceeds.

10 This invention preferably contemplates the use of an expandible mandrel, such as is presented in the companion application, Serial No. 60,538, filed October 15, 1926, which has been filed as a division of this case.

15 Now patent No. 1,627,729.

The accompanying drawings show for purposes of illustration the method of carrying out the invention and one of the many possible embodiments in which the invention 20 may take form.

Fig. 1 is a side elevation of winding mechanism with associated adhesive applying devices;

25 Fig. 2 is a plan view of the device shown in Fig. 1;

Fig. 3 illustrates a roll of paper made in accordance with the present invention.

Reference is now made to the drawings, which show one form of winding mechanism 30 used for winding paper into rolls, together with a form of adhesive applying devices associated with the same in accordance with the present invention.

The web of paper "A" comes from the stock rolls in the usual fashion and passes between a roll 20 and a slitter 21 where it is cut into one or more webs and is trimmed, as and if desired. The paper then passes underneath a large drum 22 and about a 40 power driven drum 23 in the usual manner. A pinion 25 meshes with gears 26 and 27 to drive the drums in unison. The drums 23 and 24 are separated a short distance and a mandrel 28, of the character above referred 45 to, is adapted to be rested on top of the drums and to have the paper wound thereon.

Underneath the drums 22, 23 and 24 there is arranged an adhesive receptacle 29 adapted to be filled with adhesive material 50. The receptacle 29 is carried on wheels 31 which rest on tracks 32 so that the adhesive container can be moved out from under the drums. A drum 33 is supported in bearings 34 in the lower part of the tank 29, the drum being partly submerged in the adhesive. An adhesive applying roll 35 is carried on arms 36 and 37, which arms are pivoted on shaft 34'. A pinion 38 at the 55 end of the drum 35 is adapted to mesh with the gear 26 on the drum 23 and with a gear 39 on the shaft 34'. The arms 36 and 37 are each connected through shackles 40 and 41 to leaf springs 42 and 43, and these springs are connected by arms 44 and 45 to a shaft 60 65. They are keyed to this shaft by keys

47. The shaft 46 is mounted in bearings 48 to support it from the receptacle 29. One end 49 of the shaft is squared, as indicated, and extends out a little way from the bearing 48.

The main frame 50 of the winding machine has a transverse aperture 51 through which a short shaft 52 passes, the inner end of the shaft having a squared hole to fit the squared end of shaft 46, and an arm 53 is pinned to the outer end of the shaft 52. A loosed key 54 is passed down into a slot in the frame so as to prevent the shaft 52 from sliding in the aperture 51. A long arm or lever 54 is pivoted at 55 in the end of the arm 53. The outer end of the lever 54 is provided with a follower 56 adapted to follow threads 57 on an extension of the shaft 58 on which roller 24 is mounted. A shelf 59 is adapted to hold the arm 54 when it is 80 85 90 95 100 105 110 115 120 125 130

The device is shown in full lines, in the position that is assumed when a pasted tube is being prepared on the mandrel 28. The web of paper after passing through the slitting and trimming mechanisms (where such mechanisms are used), is passed under the drums 22 and 23 and is brought up over and around the mandrel 28. The paper and mandrel rest upon the cylinders 23 and 24 and, as these cylinders are power driven, they draw the paper from the stock roll and wind it onto the mandrel. When the operator is about to start making a roll he raises the arm 54 from the shelf 59, as indicated in dotted lines in Fig. 2, and places the arm on the threads 57. This will bring the paste applying roll 35 from the dotted position in Fig. 1 up to the full line position and will bring gear 38 into mesh with gear 26. Then, as power is applied to slowly revolve the drums 23 and 24, the pasting mechanism will also be revolved and paste brought against the paper. The operator also passes a short length of clean unpasted paper about the mandrel so as to protect the mandrel from the paste. The amount of this paper should be just enough to cover the mandrel. As the paper is drawn through the walls and wound onto the mandrel, it is coated with paste as long as arm 54 rests on the threads 57. While the parts are in the position indicated in Fig. 1, a definite amount of paper will be drawn through the machine and a core of predetermined size will have been prepared before the arm 54 drops off the end of the threaded shaft 57. When this event occurs, a spring 60 connected between link 36 and the bottom of the tank 29 will pull the adhesive roll 35 down away from the paper. This will break the driving connection, and the pasting apparatus will cease to function. The paper will then continue to be drawn through the machine and the roll

formed up to full size, such as is indicated in dotted lines, in the usual manner. The mandrel may then be collapsed and withdrawn, and the finished roll is ready for shipment. The pasted core supports the inner layers of paper so that they do not unroll and fill up the hole.

It will be noted that the springs 42 and 43 act not only as levers for raising the 10 paste applying roll into position, but they also squeeze the roll against the paper.

In using such a mandrel in the paper mill, as indicated in Fig. 1, it is expanded to the predetermined diameter, and a turn of paper is passed about the mandrel, after which further paper is drawn on through the pasting mechanism, as above described. After the roll of paper, such as is indicated in Fig. 3, is completed, the mandrel is collapsed and removed from the roll leaving an opening, the walls of this opening being made of freshly pasted paper forming a core to prevent the unwinding of the paper. In many mills, it is customary to 25 wind two or more rolls simultaneously, and, where this is the case, the slitter cuts the paper to the proper width and the rolls are readily broken apart after the mandrel has been removed.

30 In the printing establishment, a mandrel identical with that used in the paper mill, except that it may be shorter as it handles but one roll of paper at a time, is used. The mandrel is collapsed, then inserted into the 35 opening in the roll and expanded to grip the sides or walls of the opening. The mandrel used in the printing establishment should preferably permit of a slightly greater expansion than the one used in the paper mill, 40 as it must be expanded against the core far enough to grip it tightly. The mandrel and roll may be accurately lined up by placing the ends of the mandrel at the end of the roll. As above pointed out, the mandrel 45 does not travel when it is being expanded. Next the mandrel is locked in place, and it is then impossible for the mandrel to loosen in the roll. The usual brake mechanism is applied to the shaft of the mandrel, and the 50 paper is run off through the press in the usual manner, friction being applied to the shaft for the usual purpose.

It will be noted that in using paper off a mandrel in the manner above indicated 55 all of the good paper is available for use in the press. None of it is destroyed by the locking device, as is customary in the locking devices now in use. It should further be noted that the paper lost in making the 60 pasted tube is substantially the same amount of paper as is mutilated by the locking devices now in use.

While it is preferable to make the paper core out of paper which is to be wound into a roll, it is, of course, obvious that the man-

drel could be used on a prepared core and that this prepared core might be either the ordinary spirally pasted cylinder or a prepared cylinder made by winding paper in the fashion indicated in Figs. 1 and 2, these 70 cores being stored for use.

By carrying out the handling of paper in the method above indicated, it is obvious that the great expense attendant upon shipping iron pipes to and from the paper mill 75 and printing establishment will be eliminated, together with the fixed charge for the investment in these pipes and the expense and trouble incident to accounting for and handling them. The pasted paper cores are 80 made from paper which is readily available in the paper mill, and the loss resulting from using this paper to make the cores is comparable with that now brought about by mutilating the inner portion of the roll 85 by affixing the locking devices necessary for applying the friction drag in the printing press.

What is claimed is:

1. The combination with a paper winding 90 mechanism having two spaced apart drums upon which a mandrel for winding the paper may rest, and devices for driving the drums; of an adhesive applying mechanism, and means for bringing it into operative 95 relation with one of the drums whereby paper passing about the drum may be coated with adhesive.

2. The combination with a paper winding 100 mechanism having two spaced apart drums upon which a mandrel for winding the paper may rest, and devices for driving the drums; of an adhesive applying mechanism underneath one of the drums, and means for bringing it into operative relation with one 105 of the drums whereby paper passing about the drum may be coated with adhesive.

3. The combination with a paper winding 110 mechanism having two spaced apart drums upon which a mandrel for winding the paper may rest, and devices for driving the drums; of an adhesive applying mechanism, means for bringing it into operative relation with one of the drums whereby paper passing about the drum may be coated with adhesive; and means for restoring the adhesive applying mechanism to an idle position after a predetermined length of paper has been coated.

4. In paper handling machinery, the combination with devices for winding a roll of paper onto a mandrel including two spaced apart power driven drums upon which the mandrel may rest, of adhesive applying devices including a movable adhesive roll adapted to be brought against the paper as it passes into one of the drums.

5. In paper handling machinery, the combination with devices for winding a roll of paper onto a mandrel including two spaced 130

- 4
- apart power driven drums upon which the mandrel may rest, of adhesive applying devices including a movable adhesive roll adapted to be brought against the paper as it passes into one of the drums; and means for automatically discontinuing the operation of the adhesive applying devices after adhesive has been applied to a predetermined length of paper.
- 10 6. In paper handling machinery, devices for making a paper core on a mandrel, said devices including a pair of spaced apart drums upon which the empty mandrel is adapted to rest, mechanism for driving the drums so that paper may be wound onto the mandrel to form a roll, an adhesive apply-
- ing mechanism adjacent one of the drums for coating the paper with adhesive.
7. In paper handling machinery, devices for making a roll of paper having a paper core, said devices including a mandrel, a pair of spaced apart drums upon which the empty mandrel is adapted to rest, mechanism for driving the drums so that paper may be wound onto the mandrel to form a 20 roll, adhesive applying mechanism adjacent one of the drums for coating the paper with adhesive; and means for automatically discontinuing the operation of the adhesive applying mechanism after adhesive has been 25 applied to a predetermined length of paper.

GEORGE W. DINGEE.
